WITNESS:

UNITED STATES PATENT OFFICE.

MONDEST C. RICHARDS, OF FLINT, MICHIGAN.

CHILD'S VEHICLE.

Application filed May 18, 1923. Serial No. 639,918.

To all whom it may concern:

Be it known that I, MONDEST C. RICHARDS, a citizen of the United States, residing at Flint, in the county of Genesee and State of Michigan, have invented new and useful Improvements in Children's Vehicles, of which the following is a specification.

This invention relates to an improved child vehicle which is adapted to be propelled by the feet, the general object of the invention being to so construct the vehicle that it can be used with or without a seat, in the latter case the operator would stand upon the vehicle and use one foot to propel the same.

Another object of the invention is to provide means whereby the vehicle can be steered.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:

Figure 1 is a side view of the device.

Figure 2 is a front view thereof.

Figure 3 is a section on line 3—3 of Figure 1.

Figure 4 is a section on line 4—4 of Figure 2.

Figure 5 is a side elevation of the vehicle when used without a seat.

In these views 1 indicates the base which has wheels 2 at its rear and 3 indicates the steering post which is connected by a hinge 4 with the front end of the base. The

hinge is secured to the base by a bolt 5. A wheel 6 is carried at the lower end of the steering post and a handle 7 is arranged at 45 its upper end. A seat 9 is detachably connected to the base by means of the spring strap 10 which is fastened to the seat having its bent ends engaging the brackets 11 on the base. By pulling one of the depending parts of the strap inwardly it may be released from its bracket and the seat then removed from the base.

When the seat is not being used the child or operator will stand with one foot on the 55 base and use his other foot to propel himself along, the steering post acting as guiding means for the device. Of course if the device is running down-hill both feet would be placed on the base. When the seat is 60 used the operator could use both feet to propel the device.

It is thought from the foregoing description that the advantages and novel features of my invention will be readily apparent. 65

I desire it to be understood that I may make changes in the construction and in the combination and arrangement of the several parts, provided that such changes fall within the scope of the appended claim. 70

What I claim is:

A device of the class described comprising a base, wheels at the rear end thereof, a steering post, a vertically arranged hinge connected with the post and pivoted to the 75 front end of the base, a wheel at the lower end of the post, a handle at the upper end thereof, a seat, a spring member for supporting the same and clips on the base for receiving the extremities of the supporting 80 member.

In testimony whereof I affix my signature.

MONDEST C. RICHARDS.
